UNITED STATES PATENT OFFICE.

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed June 3, 1922. Serial No. 565,765.

To all whom it may concern:

Be it known that I, FRED L. MACKENZIE, a citizen of the United States, residing at Beverly, in the county of Essex and State of Massachusetts, have invented certain Improvements in Fastening-Inserting Machines, of which the following description, in connection with the accompanying drawings, is a specification, like reference characters on the drawings indicating like parts in the several figures.

This invention relates to means for presenting work pieces to machines for operating upon them and is illustrated as embodied in a fastening-inserting machine of a type used in the manufacture of boots and shoes.

Fastening-inserting machines, as well as many other machines used in the manufacture of boots and shoes, are often supplied with means arranged to support the work while it is being operated upon and with means for feeding the work toward and past the operating instrumentalities of the machines. It is an object of the present invention to provide an improved work support, of a character well adapted for use in fastening-inserting machines, so organized that the work support and the stopping and starting of the machine are controlled by a single controlling member, for example a treadle, which is displaced to start the operation of the machine. In the illustrated construction the work support, during the operation of the machine, is sustained by a spring which is automatically compressed when the machine is brought to rest after operating on the work, thereby withdrawing the work support and permitting the work to be readily removed and a new piece to be presented.

To facilitate the controlling of the machine by a single controlling member or treadle, cyclically operating means are provided, in accordance with a feature of the invention, normally disconnected from the work support during the operation of the machine but arranged to be connected to the work support when the controller or treadle is released thereby causing the withdrawal of the work support as the machine

comes to rest. In accordance with another feature of the invention and as illustrated, means is provided for locking the work support in withdrawn position, operative, when the controller or treadle is again displaced to start the machine, to release the work support and cause it to be returned by its spring to its operative position.

In accordance with still another feature of the invention, the illustrated machine is provided with work-feeding means operated preferably by the same power-transmitting means which operates the work support withdrawing means. This work-feeding means, as illustrated, operates in each cycle of operation irrespective of whether the work support withdrawing means is ineffective by reason of being unlocked from the work support or is effective by reason of being locked thereto.

While the invention is disclosed herein as embodied in a fastening inserting machine, it should be noted that in various of its aspects its utility is not limited to use in connection with such machines.

With the above and other objects and features in view the invention will now be described in connection with the accompanying drawings and pointed out in the claims.

In the drawings, Fig. 1 is a view in side elevation of a machine illustrating one embodiment of the invention;

Fig. 2 is a detail view of a cam and lever mechanism for operating the work support of the machine of Fig. 1;

Fig. 3 is a view in side elevation of the upper part of the work support showing details of the work feeding means;

Fig. 4 is a similar view taken from the side opposite that shown in Fig. 3;

Fig. 5 is a detail view of the work support retracting mechanism;

Fig. 6 is a similar view partly in section looking from the right in Fig. 5; and

Fig. 7 is a detail illustrating the manner in which the work is operated upon.

In the illustrated machine a staple fastening mechanism is provided for inserting fastenings into the work, the said mecha-

nism being preferably, though not necessarily, of the type shown in Patent No. 1,016,930, granted Feb. 13, 1912, on application of William H. Borden. In this mechanism 5 wire is fed from a reel 10, cut into pieces of fastening length, formed into staples and driven through the nozzle 12 into work supported upon a work support indicated in general by the reference character 14, Fig. 10 1 of the drawings.

In the illustrated construction the work support 14 comprises a post 16 slideable vertically in bearings 18 provided upon a bracket 20 bolted to the standard 22 of the machine. 15 Secured to the upper end of the post 16 is a cap 24 having a bracket extension 26 upon which is adjustably mounted the combined work support and clinching plate 28. As shown, the bracket extension 26 is provided 20 with a recessed portion to receive the lower end of the member 28 for vertical adjustment, bolts 30 being provided to secure the member fixedly in position on the extension 26, the said bolts extending through slots in 25 the member 28. Upon loosening the bolts 30 the member 28 is adjusted vertically through the operation of the screw threaded member 32, and after the desired adjustment the bolts are again manipulated to secure the 30 plate 28 fixedly in position on the bracket extension 26. As most clearly shown in Figs. 3 and 4, the upper end of the member 28 presents an upper horizontal surface at 35 upon which the work may rest while it is being presented to the staple fastening mechanism, the said member having further a projecting portion shown in dotted lines at 38 in both of the figures which is located directly under the nozzle 12 so that as the 40 fastenings are inserted they may be clinched, if desired, to insure perfect setting of fastenings in the work.

Means is preferably provided for feeding the work over the work supporting surface 45 of the work support, the said feeding means comprising, in the construction shown, a pair of toothed wheels 40 mounted rotatably upon a shaft provided in a plate extension 42 integral with, or fixedly secured to, the cap 24. It will be clear from an inspection 50 of Figs. 3 and 4 that peripheral portions of the wheels 40 embrace the extension 38 of the work support 28, the arrangement being such that the toothed portions of the wheels 55 40 extend slightly above the work supporting surface 36 of the work support 38 so as to engage with the lower surface of the work supported on the work support to effect 60 feeding improvements of the work over the said surface. For rotating the toothed wheels 40 there is provided in the illustrated construction a pawl and ratchet mechanism 65 consisting of the ratchet wheel 46 fixedly secured to the bearing shaft of the wheels 40 so that as the ratchet wheel is turned the

feed wheels 40 are also rotated to cause feeding of the work. For operating on the ratchet wheel 46, there is provided a pawl 48 mounted at 50 upon a bell crank 52, the latter turning freely upon an axis concentric with the bearing shaft of the ratchet wheel 46, the pawl being held in engagement with the ratchet wheel by a spring indicated at 56. Pivoted to another portion of the bell crank 52 is a link 58 which is oscillated to 70 cause rocking movement of the bell crank 52 whereby intermittent movements rotative in the same direction are transmitted to the ratchet wheel 46.

For locating the work for the insertion of the first fastening there is provided a gage comprising a member 60 mounted to turn upon an axis concentric with the axis of the toothed feed wheels 40, the upper end of the gage member 60 extending above the plane of the work supporting surface 36, the said gage having a projection 62 on the other side of the point of pivotal support of the gage, the tail or projection 62 being held yieldingly by a spring 66 against an adjustable stop 68, as shown most clearly in Fig. 4 of the drawings. By means of the spring and stop arrangement the gage 60 is held in position to locate the work for the insertion of the first fastening, the tension of the spring 66 being relatively light so that the gage 60 yields readily in the direction of feeding movement of the toothed feed wheels 40 so as to back down out of the path of the work as the latter is fed over the work support. As soon as the particular piece of work being operated upon is removed the gage 60 is at once returned to operative gaging position by the spring 66. To facilitate the feeding of the work over the work support there is provided a pair of anti-friction rollers or wheels 70, one on each side of the nozzle 12 arranged to engage the upper surface of the work and mounted to co-operate with the toothed wheels 40 in feeding the work over the work support. The details of the mechanism thus far described for locating and feeding the work are similar to those shown and claimed in applicant's copending application, Serial No. 290,651, filed April 17, 1919, and issued on Nov. 20, 1923, as Patent No. 1,474,373, to which patent reference may be had for a more detailed description of the feeding and gaging mechanisms.

Means is provided in the illustrative construction for yieldingly supporting the work support during the feeding of the work and the insertion of one or of a plurality of fastenings, as may be determined by the operator. As shown, the spring means referred to comprises a spring 80 surrounding the post 16 and resting at its lower end upon an extension 82 rigid with the bracket 20 and having its upper end in contact with

a collar 84 secured adjustably to the post 16 so that upon contact of the collar 84 with the lower end of the upper bearing 18 the work supporting surface 36 will be properly spaced from the lower end of the nozzle 12. It will be clear as the description proceeds that the spring 80 is the sole support for the work supporting structure and for the work during feeding movements of the 10 work and during the insertion of the fastenings by the fastening inserting mechanism.

Means is preferably provided for retracting the work support against the resistance of the spring 80 so that work may be readily inserted for the work feeding and fastening inserting operations. In the illustrated construction this means comprises an operating mechanism operatively related to the lower end of the post 16 constructed and arranged 20 to pull the post downwardly against the tension of the spring 80 at times determined by the operator. Referring particularly to Figs. 5 and 6 it will be observed that the post 16 has a reduced rectangular portion 90 upon which slides a sleeve or box 92 adapted to be reciprocated through a link connection 94 pivoted at 96 to the sleeve and having its other end pivoted to a lever 98 which is arranged to be oscillated 25 by mechanism hereinafter described. Pivoted in a recess 100 in the rectangular end 90 of the post 16 is a pawl 102, a spring 104 being attached to the pawl to press the latter yieldingly in one direction at all times 30 so that when free to move it will always be in position to have its operative end 106 engage with a shoulder or abutment 108 on the inside of the box plate 110, the latter being removable for the purpose of inspection 35 of the parts and replacement in case of wear. Slidable inside of the box or sleeve 92 is a plate 116 having a recess at 118 shaped to provide a cam shoulder 120 on the plate.

At its lower end the plate 116 is pivoted to a rod 124 in turn pivoted at 126 (Fig. 1) to a clamp 128 on the treadle 130, the latter being normally held in its upper position of rest by a spring 132. For oscillating the 40 lever 98 which is pivoted at 140 on the bracket 20 there is provided connections leading to the cam wheel 144 on the shaft 146 which is the main shaft for the fastening inserting mechanism. As shown, the 45 cam wheel 144 has a face cam 148 in which runs a roll mounted on the lever 150 (Fig. 2) pivoted at 152 to the machine frame. Pivoted to the outer end of the lever 150, as shown in Fig. 1, is a swiveled connector 154 through which passes a rod 156, a spring 158 surrounding the rod and interposed between a collar 160 adjustable on the rod 156 and the lower surface of the connector 154, the 50 purpose of the arrangement being to provide a yielding connection between the lever

150 and the lever 98, to which the lower end of the rod 156 is pivotally connected, as shown at 164. At each revolution of the shaft 146 the lever 98 is rocked to cause reciprocation of the box or sleeve 92. If the 70 pawl 102 is in its forward operative position, as shown in Fig. 6, the shoulder or abutment 108 will engage with the pawl on the downward movement of the box or sleeve and carry the post down with it, thus spacing the upper end of the work support from the nozzle so that work may be readily introduced. This would take place at the termination of each revolution of the shaft 146 and the work support would be locked 75 in its lowered work-receiving position after the setting of each individual fastening if pawl 102 were not held out of engagement with abutment 108. Under certain circumstances this is a desirable mode of operation 80 of the machine for example if it is desired to insert but one fastening into the work. However, where it is desired to set a number of fastenings into the work it is desirable to provide means under the control of 85 the operator for causing the work support to be held in operative position during the insertion of a plurality of fastenings and for retracting or lowering the work support to work receiving position as the machine 90 comes to rest at the completion of the insertion of the fastenings. This is accomplished by the means already described, comprising the plate 116 and the cam surface 120 which 95 is adapted to engage with a projection 170 on the pawl 102 to cause tipping of the pawl to the right in Fig. 6, thus moving its operative end 106 away from the path of the shoulder 108. Hence although the box or sleeve 92 is reciprocated for each revolution 100 of the shaft and for each fastening inserting operation, no downward movement of the post 16 takes place and hence the work remains yieldingly clamped against the nozzle 105 during a plurality of fastening inserting operations. Such a construction is especially efficient in insuring proper feeding of the work through the co-operation of the toothed feed wheels 40 and the anti-friction rolls 70 on the nozzle of the machine which, as before stated, facilitate the feeding operations by providing counter pressure on the upper surface of the work 110 opposite to the parts engaged by the toothed feed wheels. When, therefore, the operator wishes to retract or lower the work support he releases the treadle 130 which, immediately returning to its upper position of rest, carries the plate 116 upwardly to position 115 the recess 118 opposite the end 170 of the pawl 102, thereby permitting the spring 104 to project the operative end of the pawl into the path of the abutment 108 on the sleeve or box 92 and hence at the termination of the 120 cycle then in progress the work support is 125 130

retracted and locked in its work receiving position as the machine is stopped. At this point it may be noted that treadle 130, through rod 190 and other suitable connections, is arranged to control the clutch which transmits power from the drive pulley 192 of the machine to shaft 146, so that the machine is started when treadle 130 is depressed and is stopped when that treadle is released. As soon as the work has been introduced and positioned against the gage 60 the operator again depresses the treadle 130, starting the machine and moving the plate 116 to cam the pawl 102 to inoperative position and hence during a number of cycles, as determined by requirements of the work and the judgment of the operator, the box 92 is reciprocated without affecting the position of the post 16. During one or a plurality of cycles of operation, the work support is supported by the spring 80 to press the work against the feed rolls on the nozzle of the fastening inserting mechanism.

While the operating means for the toothed feed wheels 40 may be provided in any desired manner by connections with the driving shaft 146, a simple construction is that which provides an extension from the oscillating lever 98, said extension being shown at 180, Fig. 1, of the drawings, as provided with a slot 182 along which the outer end of the link 58 is adjustable so as to provide an adjustable throw to the pawl carrying lever 52. It will be clear that upon each downward movement of the outer end of the lever 98 the pawl 48 will be actively operated to effect a step movement of the ratchet wheel 46 and, therefore, of the toothed feed wheels 40 and that upon each upward movement of the outer end of the lever 98 the said pawl will be retracted, riding over the teeth of the ratchet wheel 46 to a new position of engagement preliminarily to another feed movement of the feed wheels. The arrangement of the parts, therefore, is such that the piece of work is given a final feeding movement at the same time that the work support is retracted downwardly and locked in its work receiving position, both these operations following the insertion of the fastening into the work at a time when the work support is held firmly against the nozzle of the fastening inserting means. While the spring 80 is depended upon to support the work support during feeding operations and during the insertion of fastenings it does not have to be an excessively strong spring but one that will maintain contact of the feed wheels with the work just firmly enough to insure proper feeding of the latter. Because of the spring 80 in the work support the feeding means, which comprises a feed roll on the work support, is self-adjusting with respect to the work which may vary somewhat in thickness.

The construction thus provides for a substantially uniform pressure on the work within the usual practical limits, such uniformity of pressure being a matter of the greatest importance in securing uniformity in the feeding operations, it being clear that failure of the feed roll to engage the work with sufficient pressure would result in imperfect and irregular feeding of the work. In the matter of resisting the operative stroke of the driver which drives the fastening into the work, it is obvious that the inertia of the relatively heavy work support is such as to insure proper clinching of the fastening during the instantaneous impact of the driving tool.

In the drawings there is illustrated the operation of securing together two pieces of work having beveled or overlapping portion, most clearly shown in Fig. 7. It is obvious, however, that the invention may have other uses than that indicated and that the invention as a whole, as well as its various important features may have other uses and applications than that described. As before stated, in operating with the machine, the operator first places the work against the gage 60 and upon the work supporting surface 36 at a time when the work support is locked in its retracted work receiving position. The treadle 130 is then depressed immediately releasing the post 16 so that the latter is moved upwardly by the spring 80 to clamp the work against the rolls on the nozzle 12, continued depression of the treadle 130 resulting in throwing in the power means because of the rod connection 190 leading up to the cam control mechanism for the power pulley 192 on the main shaft 146. Throwing in of the clutch is followed by the insertion of a fastening, and then by a feeding operation and the insertion of another fastening, and this is repeated as long as the treadle is depressed.

Having described the invention, what is claimed as new and desired to be secured by Letters Patent is:—

1. In a fastening inserting machine having a guiding member through which the fastenings are driven, the combination of a roller mounted on the guiding member in position to engage the work to serve as a movable abutment therefor, a work support, a feed roll mounted on the work support to co-operate with the roller for feeding the work across the upper end of the work support, spring means operative to maintain the roll constantly in contact with the work during a series of fastening inserting operations, and power means for retracting the work support against the opposition of the spring to work receiving position.

2. In a fastening inserting machine having a guiding member through which the

- fastenings are driven, the combination of a roller mounted on the guiding member in position to engage the work to serve as an anti-friction abutment therefor, a work support, a feed roll mounted on the work support to co-operate with the roller for feeding the work across the upper end of the work support, spring means operative to maintain the roll constantly in contact with the work during a series of fastening inserting operations, and means for retracting the work support to work receiving position and locking it in such position.
3. In a fastening inserting machine having a guiding member through which the fastenings are driven, the combination of a roller mounted on the guiding member in position to engage the work to serve as an anti-friction abutment therefor, a work support, a feed roll mounted on the work support for co-operating with the roller in feeding the work across the upper end of the work support, spring means operative to maintain the roll constantly in contact with the work during a series of fastening inserting operations, and means automatically operative to retract the work support against the opposition of the spring to work receiving position.
4. In a fastening inserting machine having a nozzle through which the fastenings are driven, the combination of a roller mounted on the nozzle in position to engage the work, a work support, a feed roll mounted on the work support and arranged for co-operation with the roller for feeding the work across the upper end of the work support, spring means operative to maintain the roll constantly in contact with the work during a series of fastening inserting operations, and means under the control of the operator for automatically retracting the work support against the opposition of the spring to work receiving position.
5. In a machine of the class described, a work support, means mounted on the work support for feeding the work over the upper end thereof, spring means for sustaining the work support in work supporting and feeding position, and means for retracting the work support and locking it in work receiving position.
6. In a machine of the class described, a work support, feeding means mounted on the work support for feeding the work across the upper surface thereof, spring means for supporting the work support in work supporting and feeding position, means intermittently operable for moving the work support to work receiving position, and manually operable means for rendering the last mentioned means operative to retract the work support and lock it in work-receiving position.
7. In a machine for operating on work, a work support, means carried by the work support for feeding the work across the upper surface thereof, means for yieldingly maintaining the work support in work supporting and feeding position, and means for automatically retracting the work support against the opposition of said maintaining means to permit the introduction of the work.
8. In a machine for operating on work, a work support, means carried by the work support for feeding the work across the upper surface thereof, means for yieldingly maintaining the work support in work supporting and feeding position, and means for automatically moving the work support to work receiving position and locking it in such position.
9. In a machine for operating on work, a work support, means carried by the work support for feeding the work across the upper surface thereof, means for yieldingly maintaining the work support in work supporting and feeding position, means for retracting the work support to work receiving position and locking it in said position, and a manually operable member for controlling said last mentioned means.
10. In a machine of the class described, a work support comprising feeding means for moving the work over the work supporting surface of said support, spring means normally operative to maintain the work support and the work feeding means both in work supporting and work feeding positions, and power means rendered operative by the operator to compress the spring means to cause the work support to move to work receiving position.
11. In a machine of the class described, a work support comprising feeding means for moving the work over the work supporting surface of said support, spring means normally operative to maintain the work support and the work feeding means both in work supporting and work feeding positions, means automatically operative to compress the spring to move the work support to work receiving position, and a manually operable member for controlling the last mentioned means.
12. In a machine of the character described, a work support comprising a feed roll at the upper end thereof to feed work across the work supporting surface of the support, a spring for maintaining the work support in its work clamping position in which the feed roll is operative to feed the work, power operated means intermittently operable to retract the work support against the tension of the spring, and a manually operable member for rendering the last mentioned means operative at the will of the operator whereby the work support may be moved to work receiving position after any

given number of cycles of operations of the machine.

13. In a machine of the class described, a work support, spring means serving as the sole means for yieldingly maintaining the work support in work clamping position, power means for retracting the work support to work receiving position and for locking it in said position, and a controller 10 manually operable for causing connection of the power means with the work support.

14. In a machine of the class described, a work support movable between work receiving and work clamping positions, spring means for maintaining the work support constantly in work clamping position throughout a plurality of cycles of the machine, a member reciprocable during each cycle of operations of the machine and having a portion adapted to be connected to the work support for moving the latter to work receiving position, and a manually operable member for causing the connection between the reciprocable member and the work support to cause retraction of the work support at the will of the operator after one or any desired number of cycles of the machine.

15. In a machine of the class described, a work support movable between work clamping and work receiving positions, a spring for maintaining the work support constantly in work clamping position during any desired number of cycles of the machine, 35 said work support being provided with a latching pawl, a member power operated during each cycle of operations of the machine, and having an abutment or shoulder to engage the pawl on the work support, 40 and a manually operable member for controlling the described engagement of the pawl with the shoulder so that the work support may be moved to work receiving position by the power-operated member at 45 the will of the operator.

16. In a fastening inserting machine having a nozzle through which the fastenings are driven, the combination of a roll carried by the nozzle to serve as a movable 50 abutment against which the work may be clamped, a work support having at its upper end a feed roll arranged to co-operate with the roll on the nozzle to feed the work across the work supporting surface of the 55 work support, a spring for maintaining the work support constantly in work clamping position during any desired number of cycles of operation of the machine, a member power operated to compress the spring 60 and to cause the work support to move to work receiving position, and a manually operable member for determining the time of operation of the power operated member.

17. In a machine of the class described, 65 a work support, a spring for moving the

work support to work clamping position and entirely sustaining the work support during one or a plurality of operations on the work, and means controlled by the operator as to its time of operation for locking 70 the work support in work receiving position.

18. In a machine of the class described, a work support and an abutment against which the work is clamped, a spring for moving the work support to work clamping position and entirely sustaining the work support during one or a plurality of operations on the work, power operated means 75 for locking the work support in work receiving position, and means under control of the operator for connecting the power means with the work support.

19. In a machine of the class described, a work support and an abutment against which the work is clamped, a spring for moving the work support to work clamping position and entirely sustaining the work support continuously in work clamping position during a plurality of operations on the work, a treadle, power means for locking the work support in work receiving position, and connections between the treadle and the power means for rendering the latter operative at the will of the operator. 85

20. In a machine of the class described, a work support, a spring for lifting the work support and entirely sustaining the support in work clamping position, power means for moving the work support to work receiving position and maintaining it in such position while the machine is at rest, and manually operable means for releasing the work support to permit it to move upwardly toward clamping position under the action of said spring. 100

21. In a machine for operating on work, a work support, a spring serving as the sole means for supporting the support during one or a plurality of operations on the work, means for compressing the spring to retract the work support and to lock it in work receiving position, and a manually controlled cam member for unlocking the work support thus permitting it to move to work clamping position. 110

22. In a machine for operating on work, a work support, a spring serving as the sole means for maintaining the work support in work operating position, power operated means for locking the support in lowered position against the action of the spring, and manually operable means for preventing at the will of the operator effective operation of said power means. 120

23. In a machine of the class described, a work support movable between work receiving and work clamping positions, a spring for lifting the work support to work 130

clamping position and serving as the sole means for maintaining the work in work clamping position, a pawl carried by the work support, a power operated member having an abutment for engaging the pawl whereby the work support is locked in work receiving position, starting mechanism for the machine, and a manually operable member for moving the pawl to unlocking position and subsequently actuating said starting mechanism.

24. In a machine of the class described, a work support movable between work receiving and work clamping positions, a spring for lifting the work support to work clamping position and serving as the sole means of maintaining the work in work clamping position, a pawl carried by the work support, a power operated member having an abutment for engaging the pawl whereby the work support is locked in work receiving position, starting mechanism for the machine, and a manually operable member for moving the pawl to unlocking position and maintaining it in such position for one or for a plurality of operations on the work.

25. In a machine of the class described, a work support movable between work receiving and work clamping positions, a spring for lifting the work support to work clamping position and serving as the sole means of maintaining the work in work clamping position, a pawl carried by the work support, a power operated member having an abutment for engaging the pawl whereby the work support is locked in work receiving position, starting mechanism for the machine, a cam member for controlling the pawl, and a manually operable member for operating the pawl and for starting the machine in operation.

26. In a machine of the class described, a work support movable between work receiving and work clamping positions, a spring for maintaining the work support in work clamping position, power means for moving the work support to work receiving position and locking it in that position, and manually operable means for preventing the operation of said locking means throughout a plurality of cycles of operations of the machine.

27. In a machine of the class described, a work support, means mounted on the work support for feeding the work over the upper end thereof, spring means for sustaining the work support in work supporting and feeding positions during one or a plurality of cycles of operation of the machine, and power means rendered operative by the operator for retracting the work support against the opposition of the spring to work receiving position.

28. In a machine of the class described,

a work support, feeding means mounted on the work support for feeding the work across the upper surface thereof, means for supporting the work support in work supporting and feeding position, means intermittently operable for moving the work support to work receiving position, and manually operable means for rendering the last mentioned means operative to retract the work support and lock it in work-receiving position.

29. In a machine of the class described, a work support, means for feeding the work over the work supporting surface of the support, means for locking the work support in work receiving position, and means for releasing the work support to present the work in the operative plane and to condition the work feeding means for effective operation in feeding the work over the support.

30. In a machine of the class described, a work support comprising means for feeding the work over the upper end thereof, spring means for supporting the work support to engage the feeding means continuously with the work with a yielding pressure sufficient to insure proper feeding thereof throughout a plurality of cycles of the machine, and manually controllable power means for terminating the work feeding operations at the will of the operator.

31. In a machine of the class described, a work support, means mounted on the work support for feeding the work along the upper end thereof, spring means for sustaining the work support in work supporting and feeding positions, and manually controllable power means for compressing the spring and terminating the feeding of the work at the will of the operator.

32. In a machine of the class described, a work support, a spring serving as the sole means for supporting the work support in work supporting position, power means operable for moving the work support to work receiving position, and manually operable means for rendering the last mentioned means operative to retract the work support.

33. In a machine of the class described, a work support comprising feeding means for moving the work over the work supporting surface of said support, spring means normally operative to maintain the work support and the work feeding means both in work supporting and work feeding positions, means automatically operative to compress the spring means to cause the work support to move to work receiving position and to lock it in such position, and a manually operable member for releasing the work support from its locked position.

34. In a fastening inserting machine, a work support, a feed roll mounted on the

work support for feeding the work across the upper end thereof, spring means operative to maintain the roll constantly in contact with the work during a series of fastening inserting operations, power means for retracting the work support to work receiving position, and a manually operable member for releasing the work support permitting it to move to position for the first fastening prior to a work feeding movement of the feed roll.

35. In a fastening inserting machine, a work support, means mounted on the work support for feeding the work across the upper end thereof, means operative to maintain the feeding means constantly in operative relation to the work during a series of fastening inserting operations, means automatically operative to retract the work support to work receiving position, and manually operable means for releasing the work support permitting it to move to position for the first fastening prior to a work feeding movement of the feeding means.

25. 36. In a fastening inserting machine, a work support, a spring serving as the sole supporting means for the work support during the insertion of one or of a plurality of fastenings into the work on the work support, power means having connections for retracting the work support to work receiving position and locking it in such position, and starting means for controlling the power means and for releasing the work support.

40. 37. In a fastening inserting machine having a nozzle through which the fastenings are driven, the combination of work supporting and feeding means for presenting the work in successive steps in operative relation to the nozzle, power means for retracting the work supporting and feeding means and locking the same in work receiving position, a starting means for controlling the power means and for releasing the work supporting and feeding means so that the latter may present the work to the nozzle and feed the work thereto for the insertion of successive fastenings.

50. 38. In a machine of the character described comprising fastening inserting mechanism, the combination of a work support movable from work receiving to work clamping position with respect to said mechanism, a spring serving as the sole means for supporting the work support during the insertion of fastenings, power means for retracting the work support to work receiving position, and starting means for controlling the power means and for releasing the work support so that it may move from work receiving to work clamping position.

65. 39. In a machine of the character described comprising fastening inserting mech-

anism, the combination of a work support movable from work receiving to work clamping relation with respect to said mechanism, work feeding means mounted on the work support for feeding the work over the work supporting surfaces thereof, a spring serving as a sole means for supporting the work support during the feeding of the work and the insertion of fastenings, power means for retracting the work support and locking it in work receiving position, and a treadle for controlling the power means and having connections for releasing the work support so that it may move to work clamping position.

40. 40. In a machine of the character described comprising fastening inserting mechanism, the combination of a work support movable from work receiving to work clamping position with respect to said mechanism, a spring serving as the sole means for supporting the work support during the insertion of fastenings, power means for retracting the work support and locking it in work receiving position, and starting means for controlling the power means and for releasing the work support so that it may move from work receiving to work clamping position.

45. 41. In a machine of the character described comprising fastening inserting mechanism, the combination of a work support movable from work receiving to work clamping relation with respect to said mechanism, work feeding means mounted on the work support for feeding the work over the work supporting surfaces thereof, a spring serving as a sole means for supporting the work support during the feeding of the work and the insertion of fastenings, power means for retracting the work support and locking it in work receiving position, and a treadle for controlling the power means and having a connection for releasing the work support so that it may move to work clamping position.

50. 42. In a fastening inserting machine having a nozzle through which the fastenings are driven, the combination of a roller mounted on the nozzle in position to engage the work, a work support over which the work is fed, a feed roll mounted on the work support and arranged to co-operate with the roller in feeding the work, spring means for pressing the feed roll toward the roller so that the work between the roller and feed roll is constantly engaged with sufficient pressure to insure proper feeding thereof, and means for retracting the feed roll and locking it in retracted position so that work may be readily introduced for the feeding and fastening inserting operations.

55. 43. In a machine of the class described, a work supporting member, a feed roll mounted on said member, a roller mounted

above the work supporting member and arranged to cooperate with the feed roll in feeding the work over the work supporting member, a spring for moving the feed roll 5 toward the roller to cause the work to be clamped between the feed roll and roller with sufficient pressure to insure proper

feeding thereof, and means for retracting the feed roll and locking it in retracted position so that work may be readily introduced for feeding operations. 10

In testimony whereof I have signed my name to this specification.

FRED L. MACKENZIE.

Certificate of Correction.

It is hereby certified that in Letters Patent No. 1,573,081, granted February 16, 1926, upon the application of Fred L. MacKenzie, of Beverly, Massachusetts, for an improvement in "Fastening-Inserting Machines," errors appear in the printed specification requiring correction as follows: Page 2, line 59, for the word "improvements" read *movements*; page 4, lines 84 and 85, for the word "portion" read *portions*; page 5, line 21, claim 3, for the compound word "co-operating" read *co-operation*; page 8, line 22, claim 35, for the word "in" read *it*; and that the said Letters Patent should be read with these corrections therein that the same may conform to the record of the case in the Patent Office.

Signed and sealed this 8th day of June, A. D. 1926.

[SEAL.]

M. J. MOORE,
Acting Commissioner of Patents.
